FEELER DEVICE FOR LOOMS

Elmer C. Alix, Charlton City, Mass., assignor to
 Charlton Woolen Company, Charlton, Mass., a
 corporation of Massachusetts

Application July 2, 1941, Serial No. 400,818

6 Claims. (Cl. 139—273)

This invention relates to an electric feeler device for use with looms of an automatic bobbin changing type which is of such a nature as to insure a more accurate and timely function of the bobbin changing mechanism during the operation of the loom whereby when the filling upon the bobbin in the shuttle becomes substantially exhausted the bobbin changing or replenishing mechanism will be operated automatically to replace the exhausted bobbin with another having a full supply of filling thereon.

Another object is to provide a novel feeler device which will more positively control or time the ejection of the bobbin in the shuttle from which the filling has been spent during the weaving operation whereby a controlled minimum amount of filling will be permitted to remain on the bobbin when it is ejected from the shuttle thereby decreasing considerably the wastage of filling.

Another object is to provide an electric type feeler of the above character which has a plurality of feeler contacts arranged in cooperatively functioning groups which, when said feeler contacts engage the bobbin from which the filling is being spent, will more positively insure contact with a circuit closing member on said bobbin only when a desired minimum amount of filling remains on the bobbin with said minimum amount being sufficient to permit the shuttle to take two picks prior to the ejection of the bobbin.

A further object is to provide a novel construction of feeler of the above character which not only will reduce the wastage of filling normally remaining on the ejected bobbin but which will insure other associated working parts against undue wear and damage.

Referring to the drawings:

Fig. 1 is a perspective view of the feeler device and a portion of the associated parts of the operating mechanism embodying the invention;

Fig. 2 is an end view of the device illustrated in Fig. 1.

Fig. 3 is a fragmentary partial sectional view illustrating the function of the feeler contacts with the circuit closing portion of the bobbin;

Fig. 4 is an enlarged end view of the feeler contact supporting end of the device;

Fig. 5 is a fragmentary longitudinal sectional view of the feeler device illustrated in Fig. 1;

Fig. 6 is an enlarged sectional view taken as on line 6—6 of Fig. 5;

Fig. 7 is a fragmentary perspective view showing parts of the feeler contact mechanism dis-united;

Fig. 8 is a fragmentary sectional view taken as on line 8—8 of Fig. 5 and looking in the direction indicated by the arrows; and

Fig. 9 is a slightly enlarged fragmentary sectional view taken as on line 9—9 of Fig. 5.

The idea of using electric feelers having feeler contacts for engaging a metallic sleeve on a bobbin to close a circuit to a solenoid which, in turn, causes the standard bobbin ejection and bobbin replacement mechanism of an automatic loom to function is not new in the art. Such feeler devices, particularly those of the type which function cooperatively with a metallic sleeve on the bobbin, in most instances in the past, embodied only two separately functioning feeler contacts, which had to both engage the metal sleeve of the bobbin in order to function. In many instances such feeler devices either had a pointed contacting end which would tend to 20 cut through the filling and make contact with the metal sleeve through the filling sooner than desired and, in other instances, such contacting members had a wide area contacting end which did not always make contact with the metal sleeve as soon as desired thereby causing too much yarn to be spent from the bobbin prior to bringing the ejecting and bobbin replacing mechanism into play. In the latter instance, if a piece of lint or the like adhered to the point of one of 25 the feelers so as to break the contact of the feeler with the metal sleeve the device would fail to function. This is because both contacts in all instances had to make contact with the metallic sleeve in order to insure the energizing of the solenoid.

It has been found from past experience that it is this particular part of the feeler which introduced most of the difficulties with devices of this nature. It, therefore, is one of the prime 40 objects of this invention to overcome the above defects through the provision of a plurality of feeler contacts arranged in separately functioning groups and so dimensioned and positioned relative to each other as to insure more positive 45 function and timing of the ejection and bobbin replacing mechanism.

Referring more particularly to the drawings the device comprises broadly a plurality of resiliently supported feeler pins 10 arranged in two 50 separately functioning sets designated, Fig. 4, as 10a and 10b. The set of feeler contacts 10a will, for ease of description, be referred to hereinafter as the plus contacts and the feeler contacts or pins 10b will be referred to as the minus contacts. The feeler contacts or pins 10a and

10b respectively form separate circuit closing means adapted to engage a metallic contact sleeve 11 carried by each respective bobbin 12. The contact pins 10a and 10b are yieldingly supported in a carrier 13 which, in turn, is slidably supported in a tubular member 14. The carrier 13 comprises a detachable end embodying a tubular casing 15 having a bearing member 16 adjacent the outer end thereof formed of a suitable insulation material and an opposed bearing member 17 formed of similar insulation material. The feeler contacts or pins 10 are slidably supported in said spaced bearings 16 and 17 out of engagement with the casing 15. The said bearing members 16 and 17 have reduced ends 18 and 19 respectively fitting internally of the casing 15 and are held therein by means of a tie rod 20 having ends 21 and 22 secured in a threaded bore formed in the respective bearing members as illustrated in Fig. 6. The bearing member 17, on the side thereof opposite the reduced portion 19, has a reduced extension 23 fitting internally of a relatively long tubular member 24 slidably supported in the bearing 14. The reduced portion 23 is provided with a plurality of longitudinal bores 25 in which are slidably supported enlarged stop members 26 carried by the respective pin members 10. Suitable coil springs 27 positioned within each of the bores 25 are adapted to fit over the ends 28 of the pin members 10 lying within the respective bores. The said spring members 27 are adapted to engage the stop members 26 adjacent one end thereof and to engage spaced metallic contact plates 29 and 30 adjacent the opposite ends thereof. The spaced contacting plates 29 and 30 are carried by a suitable annular support 31 of insulation material slidably mounted on a connecting rod 32. The connecting rod 32 has a threaded end 33 adapted to be threaded internally of a threaded bore 34 formed in the reduced portion 23. The contact plate 29 has a protrusion 35 on the side surface thereof adapted to extend within one of the bores 25 so as to align the group of contacts or pins 10a with one of said plates and the group of contacts or pins 10b with the other of said plates as illustrated by the dash lines in Fig. 4.

A suitable nut or the like 36 is adapted to urge the contact plates 29 and 30 into engagement with the adjacent end of the reduced portion 23 to hold the coil springs or the like 27 internally of the bores 25 and to cause said resilient members to constantly tend to urge the pin members 10 outwardly of the bearing 16. The plate 30 is provided with a metallic pin 37 which extends through the annular support of insulation material 31 and which is adapted to make contact with the nut 36. The plate 29 has a blade spring or the like 38 secured thereto and adapted to engage the inner wall of the tubular member 24 between the annular support of insulation material 31 and said tubular member 24. The resilient member 33 is adapted to close a circuit between the plate 29 and the inner wall of the metallic tubular member 24. The connecting rod 32 having the threaded end 33 threaded in the threaded bore 34 in the member 33 extends longitudinally of the tubular member 24, see Fig. 5. The said connecting rod 32 adjacent the end thereof opposite the threaded end 33 extends through an opening 39 in a supporting member 40 of insulation material. The member 40 is carried by a base 41 formed integral with the tubular bearing 14. The end of the

support 40 having the opening 39 therein extends through a longitudinal slot 42 formed in the side wall of the tubular member 24 to permit the tubular member 24 to be slid longitudinally of the bearing 14 and yet prevent rotation of said tubular member 24 internally of said bearing. The rod 32 has a sliding fit internally of the opening 39 so that the said rod is free to slide through said opening when the said member 24 is moved longitudinally of the bearing 14. The end 43 of the connecting rod 32 adjacent the support 40 is threaded and is adapted to receive a collar 44 having an annular groove therein fitting over the adjacent end of the tubular member 24. The collar 44 is held in position on the adjacent end of the tubular member 24 by a nut or the like 45 threaded on the end 43. A suitable cap member of insulation material 46 is also threaded on said end 43 and is adapted to overlie the nut 44 to provide an insulation shield for said nut. The connecting rod 32 internally of the tubular member 24 has a coil spring 47 thereon engaging the nut 36 adjacent one end thereof and adapted to engage a plate 48 of metallic material adjacent the other end. The plate 48 has an opening aligned with the opening 39 through which the connecting rod 32 slides when the tubular member 24 is moved longitudinally of the bearing 14. The coil spring 47 is adapted to constantly urge the tubular member 24 in a direction toward the feeler contacts or pins 10. The plate 48 extends downwardly substantially parallel with the support 40 of insulation material and is spaced from the base 41 by a U-shaped member 49 of insulation material within an adjacent groove in the base 41. A lead wire or the like 50 is secured to said plate 48 between the support of insulation material 40 and said plate, see Fig. 9. The lead wire 50 is connected, as illustrated at 51, to a solenoid 52, that is, the said lead wire has a suitable connection 51 with one end of the coil of the solenoid 52, in a conventional manner. A suitable lead wire 53 is connected to the solenoid coil opposite the connected end 51. This lead wire extends to a pole of a suitable source of electrical energy and the opposite pole of said electrical energy is grounded to the loom or may be grounded with the base 41 as desired. If grounded to the loom a suitable connection screw 54, which attaches the feeler member to the feeler stand 55, which is a conventional part of the loom, functions to ground the base 41 with said loom. The screw member 54 also provides a pivot support for the feeler member on which it may be swung to raise or lower the contacts 10.

It is to be understood that the metallic plate 48 is so dimensioned as to not engage the side walls of the slot 42 in the member 24. It is also to be understood that the diameter of the spring 47 is such that it is spaced relative to the inner side walls of the tubular member 24. By this it is meant that the plate 48 and the spring 47 do not have electrical contact with the tubular member 24.

As best seen in Figs. 1 and 2 the bearing 14 has a projection 56 on one side thereof. This projection 56 is adapted to rest on an adjustment screw 57 which functions as an adjustable stop to limit the downward movement of the feeler and of the end of the feeler member having the feeler contacts or pins 10 therein. A suitable coil spring or the like 58 tends to constantly urge the projection 56 into engagement with the contact screw 57. The coil spring 58 is attached to an

eyelet or the like 59 formed on the bearing 14. Protruding outwardly of the side of the tubular member 24, as illustrated in Figs. 1, 2 and 8 is a bracket member 60 adapted to engage a standard operating part of the loom to retract the tubular member 24 and carrier member 13 during the automatic operation of interchanging the bobbins so that the feeler contacts or pins 10 will not engage the bobbin being ejected or the new bobbin being placed in the shuttle when the bobbins are being interchanged. The part engaged by the bracket member 60 is not illustrated as it is a conventional part of the standard automatic ejecting mechanism of looms of the type with which such feelers are used.

The complete assembly described above, including the feeler contacts 10, carrier member 13, tubular member 24, bearing 12, base block 41 and solenoid 52, etc., which will be hereinafter referred to as the feeler assembly and which is attached by means of the connection screw 54 to the feeler stand of the loom is adapted to be positioned so as to be engaged by the bobbin when the conventional lay of the loom is moved back and forth in the process of weaving.

When a substantial amount of filling 61 is on the bobbin the feeler contacts or pins 10a and 10b are prevented from engaging the metallic sleeve 11 by said filling. However, when the filling has been spent sufficiently from the bobbin by repetitive movement of the shuttle back and forth across the lay of the loom, as is usual in the weaving operation, and only a small amount of said filling remains over the metallic sleeve 11 the intermittent movement of the bobbin into engagement with the feeler contacts or pins 10a and 10b will eventually permit some of the feeler contacts of said groups to engage said metallic sleeve, as illustrated in Fig. 3. This closes a circuit through said feeler contacts or pins 10a and 10b and is adapted to energize the solenoid 52. This causes the solenoid core or plunger 62 to be forced into engagement with the arm 63. The arm 63 is a conventional part of the ejecting mechanism of looms of the character described and is adapted to operate the automatic bobbin ejecting mechanism of such looms in the conventional manner. The circuit from the ends of the feeler members 10a to the solenoid is as follows:

The feeler members or pins 10a having the stops 26 thereon engaged by the coil spring 27 causes the electrical energy to flow through said pin members, through the coil springs 27 and from said coil springs 27 to the plate 30. The plate 30 being connected by the pin 37 to the nut 36 causes the circuit to flow through said pin 37 and through the nut 26 to the connecting rod 32. The coil spring 47, which engages the nut 36, also permits the electrical energy to flow therethrough to the plate 48 which is also engaged by the coil spring 47. The plate 38 being connected to the lead wire 50 closes the said circuit through said lead wire to one end of the coil of the solenoid 52. The opposite end of the coil of the solenoid being connected by the lead wire 53 to one pole of the source of electrical energy thereby closes the circuit to said source of electrical energy. The feeler contacts or pins 10b which are similarly engaged by the coil springs 27 close the circuit through said coil springs 27 through the plate 29. The plate 29 through the blade spring 38, which engages the inner wall of the metallic tubular member 24, closes the circuit through said tubular member 75

to the bearing 14 and base 41 which is grounded and thereby connected to the opposite pole of the original source of electrical energy. When the metallic sleeve 11 is engaged by at least one of each of the groups of feeler contacts 10a and 10b the circuit through the feeler member to the solenoid is thereby closed. This only occurs when a sufficient amount of the filling has been removed from the bobbin to expose a portion of the metallic sleeve 11 for engagement by at least one of each of the groups of feeler members 10a and 10b. The feeler members are so grouped and designed as to insure that a sufficient amount of filling will remain on the bobbin to permit the bobbin to travel across the lay and back into the shuttle box from which it is to be finally ejected and replaced by another bobbin having the desired initial amount of filling thereon.

The purpose of the adjustment screw 57 and associated parts is to initially position the feeler contacts in proper alignment with the bobbin for engagement with the metallic sleeve 11 of said bobbin when the desired amount of filling has been spent therefrom.

One of the essential features of applicant's invention is the provision of a plurality of feeler contacts or pins 10a and b arranged in groups electrically engaging the respective plates 29 and 30 and so spaced relative to each other as to insure that at least one of the feeler members or ends of each of said groups will simultaneously come in contact with the metallic sleeve 11 of the bobbin when a sufficient amount of filling has been spent therefrom to warrant the final travel of the bobbin across the lay and back for replacement by a fresh bobbin having filling thereon.

From the foregoing description it will be seen that simple, efficient and positively functioning electrical feeler means has been provided for bringing about the proper operation of the standard bobbin ejecting and replacement mechanism of looms of the character described.

Having described my invention, I claim:

1. An electric feeler device for looms comprising a base having a slideway therein, a tubular member slidably supported in said base, resilient means for constantly urging said tubular member longitudinally of the slideway in a direction away from said base, a member carried by said tubular member for limiting its longitudinal movement, bearing means secured to and insulated from the end of said tubular member opposite the base and a plurality of electric feeler contacts yieldingly supported in said bearing means, said feeler contacts comprising two separate groups of opposite polarity.
2. An electric feeler device for looms comprising a base having a tubular member slidably supported therein, said tubular member having a longitudinally slotted wall portion, a contact member on said base extending inwardly of said slot, resilient means engaging said contact member internally of said tubular member for constantly urging said tubular member longitudinally in a direction away from said contact member, means for limiting said movement, bearing means on the tubular member and insulated from the end of said tubular member opposite the base, a plurality of feeler members slidably mounted in said bearing means, said feeler members comprising two separate groups of opposite polarity, resilient means yieldingly urging said feeler members in a direction outwardly of said bearing means, spaced contact plates supported adjacent the inner end of said bearing means each engaged

by the respective resilient means of each of said groups of said feeler members for urging said feeler members in a direction outwardly of said bearing means, one of said plates being electrically engaged by the first mentioned resilient means for urging the tubular member in a direction away from said first mentioned contact member and the other of said plate-like members having means thereon for electrically engaging the inner wall of the tubular member.

3. An electric feeler device for looms comprising a base having a slideway therein, a member slidably mounted in said slideway, resilient means for urging said member in a direction outwardly of said slideway, means for limiting said movement, bearing means on said slidable member and insulated from the end of said slidable member opposite the base, said bearing means having spaced plate-like portions carried thereby and insulated from each other, one of said plates having electrical contact with said resilient means and the other having electrical contact with said slidable member, a plurality of contacts slidably supported in said bearing means, said contacts being separated into two groups, resilient means associated with each of the contacts of said groups, said resilient means of one of said groups having electrical contact with one of said plates and the resilient means of the other of said groups having electrical contact with the other of said plates thereby producing two separate groups of opposite polarity.

4. An electric feeler device for looms comprising a base having a member slidable therein, resilient means for urging the said member in a direction outwardly of said base, means for limiting said movement, bearing means of insulation material on the end of said slidable member opposite the base, said bearing means having spaced plate-like portions carried thereby, one of which has an electrical contact with said resilient means and the other having electrical contact with said slidable member, a plurality of contacts slidably supported in said bearing means, said contacts being separated into two groups, resilient means associated with each of the contacts of said groups, said resilient means of one of said groups having electrical contact with one of said plates and the resilient means of the other of said groups having electrical contact with the other of said plates thereby producing two separate groups of oppo-

site polarity, a solenoid supported by said base, means carried by said base having electrical contact with the solenoid and with one of said plates through the first resilient means, and said solenoid having an electrical contact with a source of electrical energy which, in turn, has an electrical contact with the other of said plates through the slidable member.

5. An electric feeler device for looms comprising a base, a member slidably supported in said base, resilient means for urging said member in a direction outwardly of said base, bearing means of insulation material on the outer end of said slidably supported member opposite the base, said bearing means having a plurality of feeler contacts slidably mounted therein and divided into two separate groups, a pair of spaced plate-like members carried by said bearing means and resilient means for urging said feeler contacts outwardly of said bearing means, the resilient means of each of one of said groups of feeler contacts being in engagement with one of said plate-like members and the resilient means of each of the other of said groups of feeler contacts being in engagement with the other of said plate-like members, a solenoid, one of said plate-like members having an electrical contact with said solenoid and the other of said plate-like members having an electrical contact with a source of electrical energy which, in turn, has an electrical contact with said solenoid.

6. An electric feeler device for use in a solenoid circuit functioning in combination with bobbin removing and replacing mechanism and bobbins each having a metallic sleeve thereon, said feeler device comprising a base having a slideway therein, a tubular member slidably supported in said base, resilient means for constantly urging said tubular member longitudinally of the slideway in a direction away from said base, a member carried by said tubular member for limiting its longitudinal movement, bearing means secured to and insulated from the end of said tubular member opposite the base and a plurality of electric feeler contacts yieldingly supported in said bearing means, said feeler contacts comprising two separate groups of opposite polarity adapted to engage with the metallic sleeve of the bobbins during the operation of the device.

ELMER C. ALIX.
